UNITED STATES PATENT OFFICE.

WILLIAM H. PERRY, OF CONCORD, NEW HAMPSHIRE.

DESIGN FOR A MONUMENT.

SPECIFICATION forming part of Design No. 23,340, dated June 5, 1894.

Application filed February 1, 1894. Serial No. 498,798. Term of patent 7 years.

To all whom it may concern:

Be it known that I, WILLIAM H. PERRY, a citizen of the United States, residing at Concord, in the county of Merrimac and State of New Hampshire, have invented and produced a new and original Design for a Monument, of which the following is a specification, reference being had to the accompanying drawing.

My design consists essentially in the shaft having a roll cornice and a cap consisting of a four sided dome and domical projections on all sides, all of which will be pointed out by figures and letters of reference.

An ordinary base 1, having four vertical sides and terminating at their top in an obtuse frustum of a pyramid 2, and pedestal 3 having four vertical sides also terminating at their top in an obtuse frustum 4, of a pyramid, is provided upon which the shaft is mounted. One or more of the vertical sides of the pedestal 3, may be ornamented with a raised tablet 5, on which to place any desired inscription.

The shaft 6, has for the main portion four nearly vertical sides, or, they may be quite vertical if desired, joining at their bottoms the frustum 4, and having their top curvi-

linear being highest at their center as shown, their highest point terminating in a frontal 7, at either side of which is a raised ornamental edge, 8, the lower lines of which may have the configuration shown at 9. Each side of the shaft has also a tablet 10, defined by a border line having the configuration shown at 11.

Rising above the raised edge 8, are the curvilinear cornice pieces 12, which at first recede and terminate at their top in an outward projecting roll as shown at 13. Above the cornice the shaft terminates in a four sided dome 14, having the domical projections 15, on all sides of its base. The letters A—B, denote the styles of finish, respectively, hammered work, and polished work.

Having described my new design, what I claim is—

The design for a monument substantially as shown and described.

In testimony whereof I affix my signature in presence of two witnesses.

WILLIAM H. PERRY.
